A. T. HUNT

MECHANICAL PENCIL

Filed May 15, 1922

WITNESS
M. C. Lessin

INVENTOR
Alfred T. Hunt
BY Walton Harrison
ATTORNEY

UNITED STATES PATENT OFFICE.

ALFRED T. HUNT, OF BROOKLYN, NEW YORK.

MECHANICAL PENCIL.

Application filed May 15, 1922, Serial No. 561,102.

To all whom it may concern:

Be it known that I, ALFRED T. HUNT, a citizen of the United States, residing in Brooklyn, in the county of Kings, city and State of New York, have invented certain new and useful Improvements in Mechanical Pencils, of which the following is a full, clear, and concise description.

My invention relates to mechanical pencils: that is, to pencil bodies made of metal and carrying small bars of black lead which are used one at a time and fed out as consumed in writing, or as needed.

The purpose of my invention is to improve the construction of the pencil, and to simplify it and cheapen its cost of manufacture.

Reference is made to the accompanying drawing forming a part of this specification, and in which like reference characters indicate like parts throughout the several figures.

Figure 1 is a side view of my improved pencil, showing it partly in central section and partly in elevation.

Figure 2 is a side elevation of the inner barrel, and parts carried thereby.

Figure 3 is a section on the line 3—3 of Figure 1, looking in the direction indicated by the arrows.

The outer barrel of my improved pencil appears at 4, and has, generally speaking, a cylindrical form. It is provided with an end portion 5 having substantially the form of a cone, and provided at its tip with a hole 6.

Mounted upon the outer barrel 4 is a clip 7, for supporting the pencil by holding it upon the clothing of the person carrying it, in the manner well known in this art.

Located within the outer barrel 4 is a nut 8, having generally a cylindrical form and of rather massive construction. The nut 8 carries a tube 9, provided with an end portion 10 of slightly smaller diameter than the rest of the tube, so as to fit snugly about a small bar 11, of graphite or other appropriate material, used as a lead for the pencil. The tube 9 extends into a hole in the nut 8, and is secured therein, either by fitting it tightly in position, or by soldering, as the case may be. The tube 9 extends nearly but not quite the full length of the nut 8, in the direction of the axis thereof.

The nut 8 is provided with a swivel head

12, integral with it and having a form indicated more particularly in Figure 1.

The inner barrel appears at 13, and has substantially a cylindrical form. It is provided with an end portion 14 cupped inwardly, as indicated in Figure 1, and thus slightly overhanging the outer edges of the swivel head 12. The inner barrel 13 is provided with indentations 14a, the form of which may be understood from Figures 2 and 3. These indentations are so formed that the inner barrel contains passage ways 15, disposed in pairs as may be understood from Figure 3. A screw eye 16 fits neatly into one pair of these passage ways, as indicated in Figures 1 and 3. This screw eye is integral with a screw stem 17, which extends through a threaded portion 18 of the nut 8 and into the tube 9. The portion of the screw stem which extends into the tube 9 fits rather snugly thereto, but without binding upon the tube. The screw is threaded, however, and so fitted to the threaded portion 18 of the nut, that whenever the screw eye 16 is turned so as to rotate the screw stem 17 relatively to the nut, the screw stem is moved in the direction of its length, and thus fed further into, or partially withdrawn from, the tube 9.

The nut 8 is secured firmly to the outer barrel 4, either by peening as indicated at 19, or by use of soft solder.

The inner barrel 13 carries a disk 20, held firmly within it by peening as indicated at 20a, or by soldering, as the case may be. The partition 20, and the portion of the inner tube shown below the same according to Figure 1, together serve as a magazine for holding a number of leads 21; that is, small bars made of graphite or other suitable material, and used in the manner well known in this art.

A rubber eraser 22 is fitted into the adjacent end of the inner barrel 13. This rubber eraser serves the double purpose of an ordinary eraser for use in rubbing out pencil marks or the like, and a stopper for closing the adjacent end of the inner barrel 13, or in other words acting as a closure member for the magazine.

A cap 23 is detachably fitted upon the end of the inner barrel 13, as may be understood from Figure 1.

For facilitating this purpose, the inner barrel 13 may be tapered very slightly adja-

cent its lower end accordingly to Figure 2, as shown.

The operation of my device is as follows:

The various parts are assembled and fitted together as shown in the drawing, and as above described. A number of leads 21 are placed in one end of the inner barrel 13, serving as a magazine, and held therein by the eraser 22, which is forced into position 10 as shown in Figure 1 and serves as a stopper, as above described. The cap 23 is next fitted into position.

A single lead 11, being placed within the tube 9, is brought into such position that 15 it may be fed outwardly under action of the screw stem 19, and used up as required. The operator by merely grasping the outer barrel and turning the head 23 may cause the screw eye 16, and consequently the screw 20 stem 17, to rotate in either of two directions. Thus the screw stem is shifted bodily but slowly in either direction of its length. Whenever the screw is turned in one direction, the lead 11 can be pushed back by 25 the operator's finger, and thus completely housed within the tube 9 and conical portion 5 of the pencil; but when the screw stem is turned in the other direction, the lead 11 is fed outwardly and thus caused to protrude 30 slightly, being thus adapted for use in writing.

I do not limit myself to the precise construction shown, as variations may be made therein without departing from my invention, the scope of which is commensurate 35 with my claims.

Having thus described my invention, what I claim as new and desire to secure by Letters Patent is as follows:

40 1. A mechanical pencil comprising an outer barrel, a nut mounted within said outer barrel and fixed relatively thereto, said nut being provided with a threaded opening and with a swivel head, an inner barrel 45 provided with a portion engaging said swivel head, so that said inner barrel is revolute relatively to said outer barrel, said inner barrel being further provided with passage ways, a screw provided with an eye 50 fitted slidably into said passage ways, said screw being further provided with a threaded stem extending through said threaded opening of said nut; and a tube carried by said nut for the purpose of holding a lead, said tube fitting snugly over the adjacent 55 portion of said threaded stem, so that said threaded stem, by moving in the direction of its own length, can actuate said lead.

2. A mechanical pencil comprising an 60 outer barrel provided with a substantially

conical portion, a nut located within said outer barrel and fixed relatively thereto, said nut being provided with a centrally disposed threaded opening, a tube secured to said nut and provided with a portion extending into said substantially conical portion of said outer barrel, a screw provided with a threaded stem extending through the threaded opening in said nut and also extending into said tube, said screw being provided with an eye, and an inner barrel 65 fitted into said outer barrel and provided with a portion engaging said nut, for the purpose of preventing said inner barrel from traveling in the direction of its length relatively to said nut and yet permitting said inner barrel to turn relatively to said nut and to said outer barrel.

3. In a device of the character described the combination of an outer barrel, a nut 70 fitted into said outer barrel and prevented from rotating relatively thereto, said nut being provided with a threaded opening, a tube carried by said nut, a screw extending through said threaded opening and thus operatively connected with the nut, said screw 75 extending loosely into said tube and making a snug fit therein, said screw being provided with an eye, and an inner barrel enclosing said eye and revolubly fitted into 80 said outer barrel, said inner barrel having generally a cylindrical form and being provided with passage ways into which said eye extends.

4. In a mechanical pencil the combination 85 of an outer barrel provided with a substantially conical end portion, a nut fitted into 90 said outer barrel and fixed in position relatively to said outer barrel, said nut having a swivel head and a threaded opening extending axially through said swivel head, and an inner barrel provided with an end portion cupped inwardly and enclosing said 95 swivel head, thus enabling said inner barrel to be turned relatively to said outer barrel, said inner barrel being made of sheet metal and provided with indentations 100 extending in the direction of the length of the barrel, so formed that the inner barrel is 105 thus provided with passage ways, a screw provided with an eye fitted slidably into said 110 passage ways, so that rotation of the inner barrel causes the screw to turn, said screw being further provided with a threaded portion extending through the threaded opening in the nut, and a tube connected with the nut and so positioned relatively thereto 115 that said screw extends into said tube.

ALFRED T. HUNT.
